UNITED STATES PATENT OFFICE.

FRANK X. MANTSION, OF PHILADELPHIA, PENNSYLVANIA.

OIL BURNER.

Application filed June 13, 1928. Serial No. 285,132.

This invention relates to oil burners, and has for an object to provide an improved construction wherein a maximum result is secured from the oil being used through the 5 use of superheated steam.

Another object of the invention is to provide an oil burner for use in domestic heat furnaces or for other places wherein steam-producing containers are provided 10 and associated with a burner structure where oil and steam are mixed together with air to secure a maximum efficiency for the fuel used.

A further object is to provide an oil burner 15 which is an improvement over my prior Patent No. 1,555,684.

In the accompanying drawing,—

Figure 1 is a vertical sectional view 20 through a burner embodying the invention; Figure 2 is a sectional view through Figure 1 approximately on the line 2—2;

Referring to the accompanying drawing by numerals, 4 represents the burner as a whole, the structure including a chamber 21 which may be of any shape but is preferably formed by the spherical wall 22. This wall is provided with a number of air openings 23, internally threaded apertures 24 and 25, and an externally threaded tubular projection 26. 25 A nipple or jet member 27 is threaded into the aperture 24, said nipple being provided with a comparatively small passageway 28, said passageway receiving steam from the pipe 20 secured thereto. The passageway 30 is preferably in line with the center of the tubular member 26 and steam passing in a jet from this passageway is caused to move past the inner end of the threaded section 35 29 of pipe 18. The threaded section 29 is threaded into a sleeve 30 which is screwed 40 into the threaded aperture 25, whereby section 29 may be adjusted longitudinally somewhat so that oil passing therefrom may be readily caught by the jet of steam passing 45 from passageway 28 and thus cause the oil to be carbureted somewhat in chamber 21 and further carbureted as it passes through the tubular member 26. This carbureted oil or mixture of oil and steam with air drawn 50 into aperture 23 strikes the under surface of the deflector or dome 31. This deflector or dome is an arc-shaped member having a turned-down peripheral portion 32, whereby the combustible gases or mixture will be 55 directed almost downwardly when leaving the deflector.

Deflector 31 is supported by a number of legs or supporting bars 33 which may be welded or otherwise secured thereto and welded or otherwise secured to a solid disk 60 or plate 34 screwed onto the tubular member 26. The deflector 31 and the disk 34 and associated parts form in a certain sense a final carbureting chamber so that the oil, air and steam when escaping from this chamber 65 present a highly combustible substance which produces a flame with little or no smoke. This flame naturally is deflected laterally somewhat so that anything placed 70 sufficiently near the burner will be heated by this flame. The main function of the flame, however, is to provide a desired heat for anything placed above the same.

It will be noted that the oil is not heated before being vaporized and consequently no 75 part of the burner will become clogged through the carbonizing of the oil. Also, it will be evident that all or substantially all of the oil is consumed.

By this method of mixing steam in the 80 presence of air with oil, a highly efficient burner is secured which may utilize oils of different kinds and secure maximum results therefrom.

What I claim is:—

1. In a burner, a burner member comprising a spherical hollow body having a discharge opening, means for directing a jet of steam across the interior of said body and through said discharge opening, means for directing oil substantially into the center of said hollow body and into the path of said steam, whereby the steam will mix with the oil and carry the oil through said discharge opening, and means forming a carbureting chamber for receiving the oil and steam from said discharge opening, said means including an arc-shaped deflector positioned so that said oil and steam will be impinged thereon, and supporting means for spacing the deflector from said discharge opening. 90 95 100

2. A burner structure, including a burner member formed with a spherical hollow body having a tubular discharge member and means for admitting steam under pressure 105 into said body and directing the same towards said discharge member, said spherical body having a plurality of air inlet openings substantially opposite said discharge member, a pipe extending into said spherical body to a point near the center, said pipe 110 extending into said body substantially at

right angles to the direction of movement of the steam entering said body whereby the steam will strike the oil substantially centrally of said body and then carry the oil through said discharge member, a plate threaded onto the exterior of said tubular discharge member, and a deflector carried

by but spaced from said plate, said deflector extending beyond said plate, the edges of said deflector acting as an annular discharge lip for the combustion mixture passing from beneath the deflector.
